UNITED STATES PATENT OFFICE
CERTIFICATE OF CORRECTION

Patent No. Des. 218,077

Dated July 14, 1970

Inventor(s) George S. Gabriel

It is certified that error appears in the above-identified patent and that said Letters Patent are hereby corrected as shown below:

In the heading to the drawings and printed specification, lines 3 to 5, "assignor to Mediservice Inc., Wallington, N. J., a corporation of Delaware" should read -- assignor, by mesne assignment, to Bergen Brupswig Corporation, Saddle Brook, N. J., a corporation of New Jersey --.

Signed and sealed this 26th day of January 1971.
